CLAIM

The ornamental design for a fruit-wedge-like perforation for a perforated pattern spoon, as shown and described.

DESCRIPTION

FIG. 1 is top plan view of a fruit-wedge-like perforation pattern for a perforated spoon, showing my new design;

FIG. 2 is a left side view thereof;

FIG. 3 is a right side view thereof;

FIG. 4 is a bottom view thereof;

FIG. 5 is a front view thereof; and,

FIG. 6 is a rear view thereof.

The broken line disclosure of spoon shapes in FIGS. 1–6 is for illustrative purposes only and forms no part of the claimed design.
